DESIGN FOR A CYCLE PEDAL

Alfred Renshaw, Didsbury, Manchester, England,
assignor to The Renold and Coventry Chain
Company Limited, Didsbury, Manchester, Eng-
land, a company of Great Britain

Application May 3, 1934, Serial No. 51,679
In Great Britain February 10, 1934

Term of patent 14 years

To all whom it may concern:

Be it known that I, Alfred Renshaw, a subject of the King of Great Britain, residing at Renold Works, Didsbury, Manchester, in the county of Lancaster, England, have invented a new, original, and ornamental Design for a Cycle Pedal, of which the following is a specification, reference being had to the accompanying drawing, forming part thereof.

Figure 1 is a perspective view from the outer end of a cycle pedal showing my design, and Figure 2 is a similar perspective view thereof from the inner end.

I claim:

The ornamental design for a cycle pedal as shown.

ALFRED RENSHAW.
